FIG. 1 is a front right perspective view of a pen with digital audio component showing my new design;

FIG. 2 is an exploded rear right perspective view of the pen shown in FIG. 1, wherein the upper end of the upper body of the pen is shown hosting a connection point for a headset and the lower end of the upper body of the pen is shown hosting a computer connection port;

FIG. 3 is an exploded rear elevational view thereof;

FIG. 4 is a top plan view of the pen shown in FIG. 1;

FIG. 5 is a bottom plan view thereof;

FIG. 6 is a left side elevational view thereof;

FIG. 7 is a front elevational view thereof;

FIG. 8 is a right side elevational view thereof; and,

FIG. 9 is a rear elevational view thereof.
